UNITED STATES PATENT OFFICE

119,851

DESIGN FOR A SAFETY POT HOOK

George Allen Wynacht, Billings, Mont.

Application January 8, 1940, Serial No. 89,349

Term of patent 3½ years

To all whom it may concern:

Be it known that I, George Allen Wynacht, a citizen of the United States, residing at Billings, in the county of Yellowstone and State of Montana, have invented a new, original, and ornamental Design for a Safety Pot Hook, of which the following is a specification, reference being had to the accompanying drawing, forming part thereof.

I claim:

The ornamental design for a safety pot hook, as shown.

GEORGE ALLEN WYNACHT.
